UNITED STATES PATENT OFFICE.

ANDREW SIMKO, OF PASSAIC, NEW JERSEY.

MONORAIL DUMP-CAR SYSTEM

1,196,402.

Specification of Letters Patent. Patented Aug. 29, 1916.

Application filed May 20, 1916. Serial No. 88,885.

To all whom it may concern:

Be it known that I, ANDREW SIMKO, a subject of the King of Hungary, residing at Passaic, in the county of Passaic and State 5 of New Jersey, have invented certain new and useful Improvements in Monorail Dump-Car Systems, of which the following is a specification.

This invention relates to certain new and 10 useful improvements in mono-rail dump car systems.

The primary object of the invention is the provision of a readily shiftable sectional single track line adapted for operatively 15 mounting dump cars thereon and is especially serviceable in connection with excavating work and other enterprises in which a change in the direction of travel of the cars is required.

20 A further object of the device is the provision of a dump car structure possessing extreme strength and adapted for movement upon a single rail, provision being made for readily removing the car from the 25 rail as well as for shifting the rail to a different position when found desirable to connect the same between different points of travel.

With these general objects in view and 30 others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views: Figure 1 is 40 a side elevation of a track section of the present form having one of the dump cars operatively positioned thereon. Fig. 2 is a top plan view thereof. Fig. 3 is an end elevation of the car with the track rail shown 45 in vertical transverse section. Fig. 4 is a vertical transverse sectional view taken upon line IV—IV of Fig. 1, and Figs. 5 and 6 are horizontal sectional views taken upon lines V—V and VI—VI respectively, of Fig. 3.

50 Referring more in detail to the drawings, it will be noted that the track consists of separate sections 10 of rails of I-beam formation and secured together in longitudinal arrangement by means of bolts 11 passing

through depending lugs 12 at the adjacent 55 ends of the rail sections while the rail is removably secured transversely of the supporting ties 13 by means of retaining pins 14.

The car 15 designed for employment upon the rail 10 consists of a rectangular receiving frame or box 16 having its bottom 17 provided with a rectangular central outlet or dumping opening 18 which opening is normally closed by means of transversely-arranged slides 19 secured in a closed position by means of latches 20 carried by the opposite sides of the frame 16 and overlying the outer ends of the slides 19 when closed.

Oppositely-arranged pairs of depending 70 side plates or legs 21 are centrally carried beneath the car bottom 17 adapted for the reception of the rail 10 therebetween and provided at their lower ends with inwardly-extending stub-axles 22 having flanged 75 wheels 23 thereon. Inwardly projecting bolts 24 are carried by the legs 21 at opposite sides of the axles 22 and are arranged with mounting strips 25 upon their inner ends and through which mounting strips 80 the inner ends of the axles 22 are journaled.

The wheels 23 are adapted to travel upon the opposite base flanges 26 of the rail 10 and between such base flanges and the oppositely projecting top flanges 27 of the rail. 85 By this arrangement it will be seen that the car 15 is mounted for travel upon the rail 10 and is prevented from accidental displacement thereof, the outer annular flanges 28 of the wheels 23 engaging the outer edges 90 of the flanges 26, 27 when the car is operatively positioned upon the track. A terminal rail section 29 is provided for the track 10 being of inverted T-shaped cross-sectional 95 area with the base flanges 30 thereof in alignment with the base flanges 26 of the rail 10 and whereby the car 15 when moved upon the track section 29 may be readily lifted vertically off of the same by reason of the absence of any top flange upon the rail section 29. 100

Oppositely sloping chute or feed boards 31 of inverted V-shaped arrangement are positioned between the inner edges of the adjacent legs 21 with the connecting point 105 or apex end 32 of the said boards positioned centrally beneath the outlet opening 18 of the car 15. The slides 19 engage the con-

- neeting apex 32 of the said boards 31 when the said slides are in their closed position, as best illustrated in Figs. 2 and 4 of the drawings.
5. A rock shaft 33 between two of the opposite legs 21 is arranged with a brake lever 34 upon its outer end, a retaining rack 35 being provided for the said lever 34. Curved brake arms 36 are carried by the shaft 33
- 10 having brake shoes 37 for engaging the wheels 23 upon the downward movement of the lever 34. Coupling rings 38 are provided at the opposite ends of the car for connecting cars together in a train.
- 15 In operation it will be understood that the track sections 10 are to be laid adjacent the point desired for loading the same and the car 15 is moved thereon, the slides 19 being closed. When the car is filled, the same
- 20 is moved over the rails 10 to the desired position whereupon the latches 20 are released and the slides 19 shiftably moved outwardly away from the car bottom opening 18 and allowing the contents of the car to
- 25 be fed therethrough passing in diverging directions over the boards 31. The car frame 16 being considerably elevated above the track 10 by means of its legs 21 and the contents thereof being fed at opposite sides of
- 30 the track by the boards 31, the dumping of the car will not interfere with the operation of the wheels 23 so that an advantageous transferring railway is provided. The rail sections 10 may be readily detached by re-
- 35 moving the bolts 11 and the sections removed from the ties 13 for changing the entire position of the track and line of travel of the car 15. The afore-mentioned bolts 24 are provided with spacing sleeves 39 between the
- 40 adjacent leg 21 and strip 25.
- What I claim is:—
1. A railway car frame for a mono-rail system having a bottom provided with a central discharge opening, opposite pairs of
- 45 depending legs carried by the said frame at opposite sides of the rail, flanged wheels carried by the said legs adapted for travel upon the said rail, and oppositely sloping feed boards positioned between said pairs
- 50 of legs and terminating in a plane outwardly of the said wheels and track when the car is operatively positioned thereon.
2. A car comprising a receptacle having a bottom arranged with a central outlet
- 55 opening, opposite pairs of leg plates depending in parallel relations from the said receptacle bottom, inverted V-shaped feed boards secured between the said pairs of legs with their apex arranged centrally be-
- 60neath the said opening, the free edges of the said boards projecting outwardly from the said legs, closing means for the said opening, and mounting wheels carried by the said legs.
- 65 3. A car comprising a receptacle having a bottom arranged with a central outlet
- 70 opening, opposite pairs of leg plates depending in parallel relations from the said receptacle bottom, inverted V-shaped feed boards secured between the said pairs of legs with their apex arranged centrally beneath the said opening, the free edges of the said boards projecting outwardly from the said legs, oppositely arranged closing slides for the said opening laterally carried by the
- 75 receptacle bottom between adjacent pairs of legs with their inner ends in contact with the said boards when in their closed position, retaining latches for the said slides, and mounting wheels carried by the said legs inwardly thereof.
4. A car comprising a receptacle having a bottom arranged with a central outlet
- 80 opening, opposite pairs of leg plates depending in parallel relations from the said receptacle bottom, inverted V-shaped feed boards secured between the said pairs of legs with their apex arranged centrally beneath the said opening, the free edges of the said boards projecting outwardly from the said legs, oppositely arranged closing slides for the said opening laterally carried by the
- 85 receptacle bottom between adjacent pairs of legs with their inner ends in contact with the said boards when in their closed position, retaining latches for the
- 90 said slides, spaced inwardly projecting bolts carried by the lower portions of the said legs, supporting strips secured to the inner ends of the said bolts, spacing sleeves arranged between the said strips and legs, stub axles carried by said strips and legs, and flanged track wheels arranged upon said axles between said legs and strips.
5. A dump car for mono-rail systems
- 95 comprising a car body having a normally closed opening in the bottom, spaced truck wheel-supporting arms carried by the car and inclined chutes positioned between the spaced arms for directing material on opposite sides of the rail and remote from the supporting wheels.
6. A dump car for mono-rail systems comprising a car body having a gate controlled opening in the bottom thereof, depending
- 100 track wheel supporting arms carried thereby, truck wheels journaled on the lower ends of the arms and adapted for riding on a mono-rail, and means carried by said car adjacent said arms and car opening for causing the contents of the car body to travel in a path remote from the truck wheels.
7. A dump car for mono-rail systems comprising a car body, depending corner legs
- 105 carried thereby, inwardly positioned truck wheels carried by the depending legs, the said legs being arranged in spaced pairs at opposite sides of the body, and means positioned between each pair of legs for direct-
- 110
- 115
- 120
- 125
- 130

ing the contents of the car body during the dumping operation outwardly of the supporting wheels and mono-rail.

8. A dump car comprising a body-portion, depending legs carried thereby, truck wheels positioned on the inner sides of the legs and journaled in the said legs, means carried by the lower ends of the legs for ro-

tatably supporting the inner ends of the truck wheels, and means positioned at opposite sides of the car body for causing the contents thereof to travel in a path remote from the supporting wheels. ¹⁰

In testimony whereof I affix my signature.

ANDREW SIMKO.
